LIGHTING DEVICE FOR GAS BURNERS

Joseph V. Kindl and John J. Slavin, Cleveland,
Ohio, assignors to The W. J. Schoenberger
Company, Cleveland, Ohio, a corporation of
Ohio

Application February 24, 1933, Serial No. 658,450

6 Claims. (Cl. 158—115)

This invention relates to a lighting device for gas burners and particularly to a device for use in connection with the burners of gas stoves.

The general object of the invention is to provide a lighting device for gas burners which will be simple in construction, and which may be conveniently mounted and readily removed as a unitary structure.

With the above and other objects in view the invention consists of certain novel features of construction, combinations and arrangements of parts, that will be hereinafter fully described, and particularly pointed out in the appended claims.

15 In the accompanying drawing:

Figure 1 is a top plan view of a conventional type of gas stove, the grille being broken away, showing the relative position of the burners and illustrating the application of the improved lighting device;

20 Figure 2 is a section on the line 2—2 of Figure 1;

Figure 3 is a fragmentary sectional view showing one of the gas and flame conducting tubes interlocking with a side wall of the hood. The dash-dotted lines showing the position of the tube before its interlocking with said wall;

25 Figure 4 is a sectional view on line 4—4 of Figure 3;

30 Figures 5 to 7 show perspective views of the parts of the hood before assembly thereof. Thus, Figure 5 shows a perspective view of the cover; Figure 6 a perspective view of the housing and Figure 7 a perspective view of the member supporting the hood upon the pilot stem.

35 Referring more particularly to the drawing, the numeral 1 designates the top frame of a stove, including the usual grille 2, beneath which are mounted conventional main burners 3. Gas is supplied to the burners 3 through tubes 5 provided with air mixers 6 and connected with a valved manifold or header 7, in turn leading to a suitable source of gas supply, not shown.

40 The lighter of our present invention, generally speaking, comprises a lighter tube 8 connected at one end to the manifold 1, and at its other end communicating with and supporting a Bunsen type of pilot burner 9. Mounted on the upper end of the pilot burner, in a manner hereinafter described, is a hood 10. Tubes 36, one for each main burner 3, leading from the hood 10 to the main burners convey gas from the latter to the pilot burner where the gas becomes ignited and conveys the flame back to the burners 3 to ignite or light the same. The pilot

light preferably burns constantly and the main burners are ignited by the issuance of gas therefrom and therefore without flashing the pilot. Any suitable means may be employed for connecting the tube 8 to the manifold and pilot, 5 such as sleeve nuts 11 and 12 respectively.

5 The pilot 9 comprises a chambered body portion 13, formed with an upstanding hollow extension or stem 14 threaded exteriorly for a greater portion of its length and terminating at its upper extremity in a smooth tip portion 15. A needle valve 16 controls the flow of gas through the chamber 26 in body portion 13, while transverse openings 17 through the walls of hollow extension 14 supply the necessary air to the gas stream. The size of these openings can be regulated by means of threaded washer 18, which also serves as a stop for a recessed or cup-shaped nut 19 provided with a threaded opening 20 in its bottom wall 21 for threaded engagement with the stem 14. A sleeve nut 27 also threadedly mounted upon the pilot stem is adapted to enter the recess 22 of nut 19 in spaced relation to the walls thereof, and when screwed home against the bottom wall 21 locks 25 the recessed nut 19 and threaded washer 18 against turning movement.

30 The hood 10, previously referred to, preferably formed of suitable gauge metal stampings, comprises a bottom wall 28, upwardly folded side walls 23 integral with the bottom wall, and a removable cap or top 24. The bottom wall 28 of the hood is formed with a centrally disposed opening 25 adapted to snugly receive the reduced unthreaded tip portion 15 of pilot stem 14. The 35 hood is rigidly supported on the stem 14 for freedom of vertical sliding movement to permit of ready removal thereof, by means of a centrally apertured supporting member 29, having upwardly extending projecting portions 30 which 40 extend through narrow slots 31 in the bottom wall of the hood and are adapted to be clinched by banding the extended ends of the prongs back upon themselves against the upper face of the bottom wall of the hood. The arrangement of 45 the prongs and slots is such that opening 32 in the supporting member will register with the opening 25 in the bottom wall of the hood when these parts are assembled. Member 29 is also formed with symmetrically arranged depending 50 flat fingers 33 adapted to removably enter the recessed nut 19 and snugly engage or grip the flat polygonal faces 27' of sleeve nut 27.

55 In the present embodiment, the sleeve nut 27 is of hexagonal shape and the equally spaced 55

5 fingers 33 are three in number, and correspond in width to the width of the faces 27' of nut 27. Consequently the fingers will engage alternate faces with wrench like effect when the hood is mounted upon the pilot. The member 29 thus serves not only to support the hood removably upon the pilot stem for rotary adjustment, but also provides convenient means for screwing up and unscrewing the sleeved lock nut 27 incident 10 to assembly operations. The lock nut adjustments, preferably made at the factory, are such that the tip portion 15 of the pilot stem will protrude through and slightly above the bottom wall of the hood, and the conducting tube openings 34 15 will face toward the main burners 3. Thereafter any necessary adjustments will be so slight as not to interfere with the desired pilot flame action, as it will be seen that the hood can be rotated within a relatively wide range without 20 causing any considerable change in height of the hood. The pilot will of course, always remain stationary, any slight vertical adjustment relative to the horizontal axis of lighter tube 8 being made at the factory, by bending or arching the 25 tube as at 35 to conform to the manifold and main burner set-up requirements submitted by individual stove manufacturers. When seated within the recessed nut 19, the fingers 33 are protected from the deteriorating and distorting 30 effect of the heat, and consequently are not liable to become jammed.

35 Each side wall 23 of hood 10 is formed with a relatively large round opening 34 for loosely receiving the inner ends of the gas and flame conducting tubes 36, one for each main burner 3, which tubes are connected at their outer ends to the main burners. Fingers 37 depending from the top portion of the wall of each opening 34 are adapted to loosely enter or fit in openings 40 or slots 48 formed in the upper portion of the inner end of each tube 36 and thus hold the tubes removably in place, the tubes being free for slight adjustment in any direction. These fingers are slightly bent at their lower ends in an 45 outwardly direction, and preferably are sufficiently flexible to facilitate assembly of the tubes in the manner illustrated in Figure 3, that is by tilting the tube upwardly to dotted line position to facilitate guiding the outwardly bent finger 50 into its corresponding slot or opening 48, then lowering the tube to full line position, and finally forcing the tube and finger 37 inwardly to a slight extent. A reversal of this operation quickly disconnects the tube from the hood, however, 55 there is no possibility of this happening accidentally after the outer end of the tube is anchored in the main burner. Removal of the housing and tubes as a unit is possible without danger of the tubes becoming disconnected accidentally, particularly if the precaution to bend the fingers 37 inwardly after assembly is 60 observed.

65 Tubular extensions 38 sleeved on the outer ends of tubes 36 for longitudinal adjustment relative thereto, are fixed in any desired adjusted position by set screws 39. Each of the tubular extensions 38 is provided at its outer end with a lip portion 40 having an opening 41 adapted to receive a nipple 42. The lower end of this nipple 70 is preferably beveled to snugly but removably fit in a correspondingly shaped opening 43 formed in each burner 3 by enlarging one of the burner holes 44 thereof. No claim is made to the means just described for connecting the gas and flame 75 conducting tubes 36 to the main burners, as this

is quite similar to the construction disclosed in Patent No. 1,134,350 dated April 6, 1915.

Whenever the burners 3 are turned on or whenever gas leaks occur, sufficient gas flows through nipples 42 into tubular extensions 38 5 and thence through tubes 36 to the hood 10 enclosing the tip portion of pilot 9 where the gas becomes ignited and conveys the flame back to the burners.

The top or cap member 24 is secured to the 10 hood by means of flat projecting portions 50, extending upwardly from each side wall of the hood, adapted to be inserted in correspondingly shaped slots 51 formed in the cover, and then bent back upon themselves against the top face 15 of the cover as best illustrated in Figure 6.

In mounting the lighter, the hood can be rotated slightly in either direction to bring the tubes 36 into axial alinement with the burner openings 43, by merely loosening threaded 20 washer 18 and sleeve nut 21. The outer ends of tubes 36 can also be elevated slightly, due to the loose fit of the inner ends thereof in openings 34 in the pilot housing, so that nipples 42 can be conveniently inserted in the openings 43, 25 without danger of the tubes becoming disconnected from the housing during this operation. This loose fit also insures a desirable supply of secondary air to the pilot adjacent the point of gas discharge from the tubes 36. The pilot 30 housing 10 and tubes 36 are readily removable as a unit for cleaning or inspection purposes, and when so removed the tubes will be held against accidental displacement by the fingers 37.

Having thus described our invention, what we 35 claim as our invention is:

1. In a lighter, the combination of a burner, a source of fuel supply therefor, a pilot, a housing for said pilot having an opening therein, a slotted tubular connection fitting loosely at 40 one end in the opening of said housing and at the other end communicating with the burner, and a finger on said housing adapted to engage in said slot for preventing accidental removal of said tubular connection from said opening. 45

2. In a lighter, the combination of a burner, a source of fuel supply therefor, a pilot having a threaded hollow stem, a tube connecting said source of fuel supply with and supporting said pilot, a hood for the pilot, a cup-shaped nut on 50 said stem, a sleeved lock nut on said stem above said cup-shaped nut, means on the hood seating in said cup-shaped nut and engaging the side walls of said sleeve nut for freely removably supporting said hood upon said stem and for 55 adjusting said sleeved lock nut by rotation of said hood, and a tube leading from said hood to said burner.

3. In a lighter, the combination of a burner, a source of fuel supply therefor, a pilot having 60 a hollow threaded stem, a hood for the pilot, a tube supporting said pilot and connecting same with said fuel supply, a recessed nut on said stem, a sleeve nut on said stem above said recessed nut, fingers on said hood engaging over 65 said sleeve nut and in the recess of said recessed nut, and adjustable means on said stem below said recessed nut cooperating with said sleeve nut to lock the recessed nut to the stem, and a tube leading from the hood to the burner. 70

4. In a lighter, the combination of a burner, a source of fuel supply therefor, a pilot, a housing for said pilot having an opening therein, a slotted tubular connection fitting loosely at one 75 end in the opening of said housing and at the 77

other end communicating with the burner, and a flexible finger on said housing adapted to engage in said slot for preventing accidental removal of said tubular connection from said opening.

5. In a lighter, the combination of a burner, a source of fuel supply therefor, a pilot, a housing for said pilot having an opening therein, a tubular connection fitting loosely at one end in the 10 opening of said housing to permit free circulation of air around said end of the tubular connection, and means extending from said housing into and through the wall of said tubular connection for preventing accidental removal of

said tubular connection from said housing, the other end of said tubular connection communicating with the burner.

6. In a lighter, the combination of a burner, a source of fuel supply therefor, a pilot having a threaded hollow stem, a tube connecting said source of fuel supply with and supporting said pilot, a hood for the pilot, a cup-shaped nut on said stem, a sleeved lock nut associated with said first mentioned nut, and means extending downwardly from the hood for freely removably supporting said hood and for turning said lock nut.
